ATTORNEY.

UNITED STATES PATENT OFFICE.

OTTO G. KLEIN, OF STE. GENEVIEVE, MISSOURI.

ENVELOP.

1,401,792.

Specification of Letters Patent. Patented Dec. 27, 1921.

Application filed June 1, 1920. Serial No. 385,665.

To all whom it may concern:

Be it known that I, OTTO G. KLEIN, a citizen of the United States, residing at Ste. Genevieve, in the county of Ste. Genevieve 5 and State of Missouri, have invented certain new and useful Improvements in Envelops, of which the following is a specification.

This invention relates to envelopes for mailing purposes and has for its principal 10 object to provide an improved form of mailing means which embodies a return envelop detachable by and for the use of the recipient whereby correspondence with mail order houses, etc., may be more conveniently 15 carried on.

The invention further contemplates the provision of a mailing medium in the character of double envelop forming blanks which can be readily folded into the desired 20 form to provide a safe and secure envelop for letters, etc., which can be mailed, sealed or unsealed as desired.

In addition the invention also contemplates the provision of means for enabling 25 a duplex envelop to be cut and folded from a single blank in such a form and shape as to provide a mailing medium having practically the same characteristics of an ordinary business letter envelop but yet at the 30 same time being capable of greater use and for many and variant purposes.

With the above and other objects which will appear as the description proceeds, the invention may be said to reside generally 35 in the details of construction, combination and arrangement of parts as will be hereinafter more fully pointed out, reference being had to the accompanying drawings wherein—

40 Figure 1 is a side elevation of the improved envelop when completely folded and ready for mailing.

Fig. 2 is a similar view, the closing flap of the envelop being open to admit the insertion of a letter within the envelop.

45 Fig. 3 is a vertical cross sectional view thereof taken on the line 3—3 of Fig. 2 and Fig. 4 is a plan view of the blank or wrapper prior to its being folded to form 50 the envelop herein contemplated.

It is the purpose of the present invention, in providing a duplex envelop of the character here illustrated, to produce an article which can be conveniently used by 55 drug or chemical companies and in fact any

mail order concerns where dealings with customers are naturally carried on by correspondence, and it aims to provide an envelop which can be used by such firms in the same manner as the ordinary business 60 envelop but which will at the same time embody an auxiliary envelop which may be used by the customers in mailing back their orders, etc., thus facilitating the exchange 65 of intelligence between the vendor and purchaser and also their mutual interests. With this end in view the envelop is formed primarily from a blank 1 designed to be substantially rectangular throughout its major portion and terminating in approxi- 70

mately triangular ends and side flaps as will be hereinafter more particularly pointed out. The rectangular portion of the wrapper is preferably spaced off evenly into three 75 sections or parts to provide upper, intermediate and lower sections designated at 2, 3 and 4 respectively, each of which is defined by the dotted line structure extending transversely of the wrapper as shown to advantage in Fig. 4 of the drawing. The 80 middle or intermediate section 3 is provided with integrally formed side flaps 5, preferably triangular as shown and in the nature of the side flaps of the ordinary envelop. This section is also provided with 85 a triangular row of perforations 6 leading inwardly from the opposite lower corners of the section 3 and spaced from the lower edges of the flaps 5 when the latter are 90 folded inwardly thus providing an outer and inner envelop. The lowermost section 4 is likewise provided with a pair of side flaps, these flaps however, as shown at 7, being of a different design than flaps 5 and 95 made so as to substantially cover the section 4 when folded with the upper edges positioned almost parallel with the upper dotted line of the section 4 and the lower edges undercut substantially as shown. At 100 the lower edge of the section 4 is provided with a bottom flap 8 and at the other end with the closure or sealing flap 9, this flap being provided with a tongue or tab 10. After having been cut to the shape as thus 105 described, the blank would ordinarily be provided with gummed edges as indicated at 8' and 10' respectively and the side flaps 7 would likewise be gummed as at 11, such flaps however being gummed only along 110 the undercut edges and upon the surface

uppermost when folded inwardly. It may be noted from a consideration of Fig. 4 of the drawings that the lower half of the blank is thus practically a duplicate of the ordinary blank from which the usual and ordinary mailing envelop is folded since the section 4 may be termed the front of the envelop which will be formed upon folding the flap 8 inwardly over the 10 turned flaps 7 to which may be glued the closing flap of the envelop being provided by the triangular portion 12 inwardly of the perforations 6. To the same extent the upper portion of the wrapper may be 15 said to constitute a separate and distinct envelop, it being apparent that sections 2 and 3 may be folded inwardly and glued together by the flaps 5 to form an envelop having the closure flap 9. Consequently, 20 out of the single blank it is possible to form two separate and distinct envelops which may be detached one from the other without impairing the utility of one of them.

In using the envelop as contemplated here- 25 in, the side flaps 7 are first folded over to the position assumed in Fig. 4 and the bottom flap 8 is then folded over until the gummed edges 11 and 8' contact and cause the flaps to adhere to one another to provide a bot- 30 tom pocket or envelop in which a letter, card or other matter may be inserted if desired.

This may, however, be left empty as it con- 35 stitutes the return envelop to be used by the consumer in corresponding with the person or firm whose name and address, etc., may be printed upon that surface of section 4 which constitutes the front of the envelop. Before the flaps 5 are folded inwardly as shown in the drawing, the pocket or envelop bearing 40 section 4 is folded inwardly along the dotted line 13 so as to lie against section 3 sub- sequent to which the flaps 5 may then be folded inwardly so as to lie outside of the envelop. Sections 3 and 4 are then folded 45 along dotted line 14 so as to lie against sec- tion 2 in which event the blank assumes the shape illustrated in Fig. 2 of the drawing. If it is desired that the matter contained within the envelop when transmitted to a 50 customer be sealed, the flap 5 which rests up against the section 2 should ordinarily have been provided with gummed surfaces so as to adhere to the inner face of the section 2 thus providing a space 16 between the section 2 and the inner opposing section 4, into which the letter, etc., may be inserted as into any envelop. The customer's return envelop, indicated at 15, forms the outermost fold of the envelop and the flap 12 thereof

60 is adapted to be covered when the flap 9 of the inner envelop is folded over and sealed, it being noted that the gummed edge 10 lies outside of or spaced off from the flap portion 12 as defined by the perforations 6.

65 The object of this is to prevent the tearing

open of the sealed flap 9 from mutilating or in any wise injuring the customer's return envelop. The folding over and sealing of the flap 9 completes the envelop and pro- 70 vides a sealed package or envelop which can be stamped and deposited in the mail. Where however it is unnecessary that the package be sealed the flaps 5 would not be gummed but on the other hand left as shown in Fig. 4 so that when the flap 9 is sealed 75 access may be had to the letter contained within the main envelop 16 merely by drawing out one of the turned in flaps 5 and with- drawing the letter, etc. It is also obvious that other arrangements may be effected 80 when it is desired to adapt the envelop for mailing packages without sealing and may be done in various ways, such as by slitting the section 3 just above the flap portions 12 so that the tongue 10 may be inserted there- 85 through when the flap 9 is folded over; or any other suitable fastening means may be employed, the idea being that the customer upon receiving the envelop can unfasten it and unfold the wrapper to reach the vendor's 90 message therein and to tear off the return envelop 15 along the perforations 6, which envelop can be used for mailing the reply. When the envelop comes sealed the same may be torn open by ripping it across the 95 upper end of the sealed flap portion 9.

From the above it will be seen that this invention provides a wrapper which can be folded to provide a double envelop structure in which separate and distinct messages can 100 be deposited, one of which envelops may be employed as a return envelop for transmitting a reply. It is also to be understood that various changes and modifications may be resorted to in the practical application of 105 the invention, provided all such modifications and alterations that are found necessary are properly within the scope and spirit of the invention defined in the appended claims.

Having thus described the invention what I claim as new and desire to secure by Letters Patent is:

1. A duplex envelop including an upper, an intermediate and a lower section, a sealing flap at the end of said upper and lower sections, side flaps extending from said lower and intermediate sections, said lower section being separated from said intermediate section by a row of perforations which extend 115 inwardly from opposite corners of said lower section to form an inner envelop and whereby the separation of said lower section from said intermediate section is facilitated.

2. A duplex envelop including a blank, 120 having inner and outer envelops detachably united, said inner envelop being foldable upon the rear wall of the outer envelop, side flaps carried by said outer envelop and having an adhesive applied thereto whereby 125 130

said flaps may adhere to the inner surface of the front wall of the outer envelop to form a pocket, said outer envelop having a sealing flap adapted to be connected to the rear wall 5 of the outer envelop to inclose the inner envelop.

3. A duplex envelop including a blank consisting of upper, intermediate and lower wall sections, said lower section being provided with flaps to constitute an inner envelop, the intermediate section being provided with side flaps foldable upon the inner envelop and inside of the outer envelop, said intermediate and lower wall sections being 10 foldable upon the upper wall section, and a sealing flap carried by the upper wall section for sealing the outer envelop.
4. A mailing device comprising a rec-

tangular blank having an end flap at each end and divided into three sections, the intermediate section being provided with a row of perforations dividing the strip into upper and lower envelop portions, side flaps carried by the perforated section and adapted when folded in to coat with the uppermost section so as to provide one envelop and side flaps carried by the lowermost section and adapted to coöperate with the lower end flap to provide the other envelop.

In testimony whereof I affix my signature 30 in presence of witnesses.

OTTO G. KLEIN.
